UNITED STATES PATENT OFFICE.

LUDVIG NELSON, OF DEARY, IDAHO.

WRENCH.

1,240,762.

Specification of Letters Patent. Patented Sept. 18, 1917.

Application filed July 19, 1916. Serial No. 110,215.

To all whom it may concern:

Be it known that I, LUDVIG NELSON, a subject of the King of Sweden, residing at Deary, in the county of Latah and State of Idaho, have invented certain useful Improvements in Wrenches, of which the following is a specification, reference being had therein to the accompanying drawing.

This invention relates to improvements in wrenches, one object of the invention being the provision of a quick acting wrench provided with means for controlling one of the jaws thereof whereby nuts may be operated upon without rounding the corners thereof and by means of which when the handle is operated upon in one direction, the nut will be firmly gripped between the jaws, and when operated in the opposite direction, the jaws will be permitted to release the nut to permit of the easy insertion or withdrawal of the wrench, yet by continuing a pressure in the same direction the nut will be unloosened thereby obviating a separate adjustment of the parts to accomplish this purpose.

A further object of this invention is the provision of a wrench of this type which is simple, durable and inexpensive in construction, and thoroughly efficient and practical in use.

In the accompanying drawings:

Figure 1 is a view in elevation taken from the rear of the jaws.

Fig. 2 is a side elevation of the wrench, dotted positions illustrating the action of the members in producing a clamping action between the jaws.

Fig. 3 is a sectional view taken on line 3—3 of Fig. 1.

Fig. 4 is a section taken on line 4—4 of Fig. 3.

Fig. 5 is a section taken on line 5—5 of Fig. 3.

Figs. 6 and 7 are detail views of the clamping member.

Figs. 8, 9 and 10 are detail views of the modified form.

Referring to the drawings, the numeral 10 designates the handle of the wrench which carries therewith the main body portion 12 having the chamber 13 open at opposite sides as at 14, and provided intermediate of its ends with the recess 15 providing the curved wall 16.

Mounted for straight line movement in the chamber of the casing is the stem 17

which has rigidly secured to the outer end thereof the outer jaw 18, while slidably mounted upon said stem is the inner or movable jaw 19.

The stem 17 is provided with the oppositely disposed threaded portions 20 for the reception of the manipulating nut 21 which is mounted within the recess 15 and is operable from without the body 12, while mounted upon said stem and adapted to be held against the wall 16 is a washer 22 having the curved face 23 for slidably engaging the wall 16 so that the body and the handle of the wrench may assume the full and dotted line positions, as shown in Fig. 2.

In order to hold the jaw 19 relatively to the body 12 and yet permit the jaw 19 to be moved a relative distance to and from the jaw 18 into nut engaging and releasing position, a radius plate 24 is pivotally connected by the screw 25 to the jaw 19, while it is slidably connected through the slot 26 and the screw 27 to the body 12.

Thus, with the point 28, as shown in Fig. 2, the center of the circle described by the wall 15 and the washer 22, the respective corners 29 and 30 of the body 12 will engage the corresponding portions of the jaw 19 and cause the same to assume the positions as shown in Fig. 2.

In the construction as shown in Figs. 8, 9 and 10, the radius plate 24' is mounted within the longitudinal recess 31 of the body 12' and in the recess 32 of the jaw 18'. In other words, the same is housed instead of disposed on the exterior of the wrench and as heretofore described.

The operation of the present invention may be reviewed as follows:

Assuming that the parts have been assembled in the manner illustrated in Figs. 2 and 3, the handle 10 is engaged and moved in the direction indicated in dotted lines in Fig. 2, causing the body portion to pivot about the point indicated by the numeral 28 so that one corner thereof will engage the corresponding inner end of the movable jaw 19 to consequently move this jaw toward the rigid jaw so that the two jaws may be arranged in an operative position on a nut (not shown). During this movement owing to the tapered formation of the chamber the body portion of course is permitted to move about the stem while the curved face of the washer 23 being engaged on the

curved wall of the recess guides the swinging movement of the body portion and owing to the fact that the stem is rectangular in cross section, rotating movement of this element is obviated. To release the jaws it is only necessary to swing the handle in the position indicated in full lines in Fig. 2 or in substantial alignment with the shank. By continuing the pressure on the handle 10 it may likewise be moved in a reverse direction so that the opposite end of the body portion will engage the corresponding inner edge of the jaw 19 to again place it in a working position and by reason of this relation of parts it will be appreciated that it is unnecessary to remove the jaws from about the nut (not shown) to again position them in an operative position. It is to be appreciated that the swinging movement is permitted by the plate having a slot therein 15 which is operably arranged about the screw 27 on the body portion.

It will be understood that the above description and accompanying drawings comprehend only the general and preferred embodiment of my invention and that various minor changes in detail of construction, proportion and arrangement of the parts may be made within the scope of the appended 20 claims and without sacrificing any of the advantages of my invention.

What I claim as new is:—

1. A wrench including a body portion having a chamber therethrough, the chamber being provided with an intersecting recess having a curved wall, a stem slidable in the chamber, a rigid jaw on the outer end of the stem, a movable jaw slidably mounted on the stem and arranged adjacent one end 30 of the body portion, a plate having one end pivotally connected to the movable jaw and having a slot in the opposite end, means engaged with the body portion and operating in the slot for connecting the opposite end 40 of the plate to the body portion, a handle projecting from the body portion, and means adjustably engageable with the stem and arranged in the recess for guiding the movement 45 of the body portion when the handle is moved in either direction to swing the 50

body portion against either portion of the inner edge of the movable jaw to consequently move said jaw with respect to the rigid jaw.

2. A wrench including a body portion having a chamber the walls of which diverge from the outer end to the inner end, the chamber being provided substantially midway the ends thereof with an intersecting 60 recess having a curved wall, a stem square in cross section slidable in the chamber, a rigid jaw on the outer end of the stem, a movable jaw slidably mounted on the stem and pivotally connected to the body portion, 65 a handle projecting from the inner end of the body portion, and means adjustably engageable with the stem and arranged in the recess and operating on the curved wall thereof for guiding the movement of the 70 body portion when the handle is moved in either direction to consequently swing the body portion when adjusting the movable jaw with respect to the rigid jaw.

3. A wrench including a body portion having a chamber therethrough, the walls of which diverge toward the inner end, the body portion being also provided with a recess which intersects the chamber approximately midway the ends thereof, the recess 80 being provided with a curved wall, a stem square in cross sections slidable in the body portion and having threads on the inner end thereof, a rigid jaw on the outer end of the stem, a movable jaw slidably mounted on 85 the stem and pivotally connected to the body portion to permit of the swinging movement of the body portion with respect thereto, a washer arranged on the stem and having a curved face engageable with the curved wall 90 of the recess, a nut operably mounted on the stem and operable from without the body portion so as to adjust the relative position of the parts, and a handle projecting from the inner end of the body portion for swinging the body portion in either direction to 95 adjust the movable jaw, the movement of the body portion being guided by the washer operating on the curved wall of the recess.

In testimony whereof I affix my signature. 100

LUDVIG NELSON.
